UNITED STATES PATENT OFFICE.

GEORGE R. BACON, OF BROOKLYN, NEW YORK.

TYPE-MOLD.

SPECIFICATION forming part of Letters Patent No. 309,596, dated December 23, 1884.

Application filed December 13, 1883. (No model.)

To all whom it may concern:

Be it known that I, GEORGE R. BACON, a citizen of the United States, residing in the city of Brooklyn, county of Kings, and State 5 of New York, have invented certain new and useful Improvements in Type-Molds, fully described and represented in the following specification and the accompanying drawings, forming a part of the same.

10 In said drawings, Figure 1 is a longitudinal sectional elevation as seen from the matrix side of the mold now in common use; Fig. 2, an elevation of the improved mold as seen from the matrix side; Fig. 3, a left-hand end 15 elevation of the same. Fig. 4 is a plan view of the interior of the bottom member of the improved mold. Fig. 5 is a plan view of the interior of the top member of the improved mold. Fig. 6 is a longitudinal section of the 20 mold on line *x* of Fig. 3, the parts being seen in the same relation as are those of Fig. 1. Fig. 7 is a cross-sectional elevation on the line 25 *y* of Fig. 2. Fig. 8 is a detail view showing construction of the nick-formers; and Fig. 9 is a sectional elevation of a portion of a mold, showing the common mode of securing the 30 nick-formers.

In constructing the molds for type-casting machines it has heretofore been the common 35 practice to form the bed-piece in both the top and bottom members of the mold of a single piece, with attached lifts suited to the thickness of the body of the type to be cast, which lifts thus made in detached pieces require to 40 be attached in place by screws, and to be most accurately fitted, so as to form a close joint with the carriage in each member of the mold. In practice the hot metal used causes an unequal 45 expansion of the many pieces composing the mold, which vary in relative size, and frequently these lifts move so far from the bed as to not only destroy this nicely-formed joint, but make an opening into which the molten 50 metal may enter and form a side sprue on the corner of the type-body. These lifts also slue out of place far enough to project a corner that forms a hard-metal abutment, against which the soft matrix is brought into contact each time a type is cast, which last condition 55 of things soon results in great injury to the matrix, which is a costly part of a type-cast-

ing machine. The old construction, also, has the nick-formers made from short lengths of half-round wire entered into and held in recesses cut in the under surface of the lift that 55 is attached to the bed-piece, which wires thus present portions extending beyond the lift over the low part of the bed-piece of the mold to operate as nick-formers; and although these extending portions or nick-formers are 60 closely fitted to the face of said bed-piece, they are unattached thereto, and are therefore liable to curl up, in consequence of uneven expansion, and form a space beneath them, into which the metal may flow and form a sprue, 65 which not only spoils the type, but frequently causes the nick-formers to be bent out of place in removing the cast type from the mold, and another defect is in the jet-piece.

The purpose and object of the present invention is a construction of parts that will 70 obviate these defects; and the invention consists in forming each member of the mold of a solid body-block and bed-piece, in uniting said body-block and bed-piece together by a 75 longitudinal tie and to the bed-plate by screws, in providing the mold with solid nick-formers, and in the mode of securing the jet-pieces in place.

For the purpose of this specification the 80 type-molds are alone illustrated herein, their mode of mounting and use in a type-casting machine being the same as those of ordinary construction, and therefore well understood by persons skilled in the art of casting type. 85 It may be explained, however, that the lower member of the mold is usually attached in an inclined position to a carrier, and that the upper member is hinged to said carrier so as to open and close, while the matrix, which 90 co-operates with the said members of the mold, is hinged to the carrier by a spring, and capable of moving slightly to and from the mold as the latter closes and opens.

In the common construction (see Fig. 1) 95 the lower member of a type-mold consists of a bed-plate, *A*, by which it is attached to the carrier, which plate supports a long bed, *B*, that is made of a single piece, and provided with a plate or lift, *C*, formed of a separate 100 piece of a thickness equal to that of the body of the type. The upper member of the mold

consists of a bed-plate, D, by which it is attached to the carrier, of a long bed, E, in a single piece, and a lift, F, formed of a single piece. The bed B of the lower member is 5 provided with nick-formers *a* by means of short lengths of half-round wire fastened in place by being inserted in grooves in the lift C and clamped between it and the bed B, the projecting parts of the nick-formers, or 10 those portions which form the nicks in the types, lapping onto the face of the bed B. The lift carried by the upper member of the mold has grooves *c* so arranged relatively to the nick-formers *a* as to provide for the longitudinal 15 adjustment of the upper and lower members of the mold when the opening *o*, that determines the size of the body of the type, is to be increased or diminished. The bed B is secured to the bed-plate A by means of screws 20 *b d*, and the lift C is held to the bed by three screws, *g*, only two of which are shown. The bed E is secured to the bed-plate D by screws *h k*, and its lift F is held to the bed by three screws, *q*, only two of which are illustrated. 25 The screws *g q* respectively pass through the bed-plates A D and beds B E, and serve in some degree to aid in holding said beds to their bed-plates.

In the improved construction the bed-plates 30 A D of both members of the mold are of like construction, and perform the same functions as in the old construction, and, like them, the plate A has holes *e*, by which the lower member of the mold is attached, through screws, 35 to its carriage, while the plate D is provided with tapped holes to receive screws attaching the top member to its carriage. In the new construction each member of the mold is provided with a bed composed of two pieces, 40 one constituting the bed proper, and the other what may be termed a "body-block." Thus the bed-plate A has a bed-piece, 10, secured to said plate by means of two screws, 11 12, and a body-block, 13, that is firmly secured 45 to the plate by means of two screws, 14 15.

The bed-plate D has a bed-piece, 16, secured to the plate by means of two screws, 17 18, and a body-block, 19, secured to the plate by two screws, 20 21.

50 The body-blocks 13 19 and the bed-pieces 10 16 are each made in a single piece of metal, preferably fine steel, and these blocks and bed-pieces are relatively of such thickness as will cause the body-blocks to project beyond the 55 bed-pieces sufficiently to correspond with the thickness the type is to be, or, in other words, form, when the two members of the mold are properly adjusted longitudinally, a recess suited to the formation of the body of a type.

60 The body-block 13 and abutting companion bed-piece, 10, and the body-block 19 and abutting companion bed-piece, 16, are respectively held in their closely-fitting longitudinal relation by means of longitudinal screws 22 23, 65 that enter tapped recesses in the bed-pieces.

The body-blocks 13 19, it will be observed,

embody in a single piece the necessary dimensions to provide the space within which to cast the body of the type, and hence avoid the addition of a separate piece for that purpose, 70 as the lift C in the old construction. Thus the body-blocks 13 19 are composed of single solid blocks of metal about equal in extent to those composing the bed-pieces 10 16, whence results an even expansion and contraction of the 75 entire bed under the influence of the heated metal used in the molds, which structure also avoids the defective operation heretofore pointed out as due to the use of thin pieces of metal, as the lifts of the old structure. 80

The improved structure also enables the use of the four lateral and the longitudinal holding-screws, as 11, 12, 14, 15, and 22, or 17, 18, 20, 21, and 23, whereby the body-blocks 13 19 and bed-pieces 10 16 are strongly secured to the 85 bed-plates A D and against longitudinal displacement, the absence of holding-screws for lifts, as in the old device, permitting their use without weakening the parts.

This improved structure further enables the 90 nick-formers to be strongly constructed and rigidly attached throughout their entire length, as will now be explained, it being first understood that the slots 28, formed in the face of the body-block 19, are the same as slots 95 formed in the lift F of the old construction, the same being cut to conform to the nick-formers and permit the upper and lower members of the mold to be adjusted longitudinally for the casting of types ranging one or more 100 lines in size.

The bed-piece 10 is provided for a suitable distance with slots 30, having undercut or recessed sides, and the nick-formers 31 are fashioned out of metal, and have a body-formation, preferably semicircular, as seen in transverse section, Figs. 7 and 8, that is suited to the formation of the nicks in types. They are constructed with shoulders 3, that constitute rests by which they are snugly seated 110 upon the bed-piece 10, and with a downward extension that is provided with lateral side projections adapted to fit within the recessed sides of the slots 30 and retain them securely in place. As embodied herein, this means 115 for securing the nick-formers in place upon the bed-piece is an ordinary dovetail joint. Thus constructed, suitable lengths may be driven into the slots 30, and thus be strongly secured throughout their entire length, both 120 by the shoulders 3 and extension projecting into the slots 30, thus practically riveted in place and forming a solid body with the bed-piece 10, that avoids any loose part that may curl up or become disarranged, either by the 125 heat of the metal or otherwise. This construction also enables the nick-formers to be extended in the piece 10 as far as may be necessary to suit large sizes of type and cause them to be cast with nicks extending from 130 side to side, whereas in the old construction it was desirable to limit the extent of these

nicks in types of a large size, so that said nicks terminated in the body of the type and did not reach one edge.

The recess for the reception of the matrix is provided between register-pieces 50 40, the latter of which has a cap called a "stool," 41, secured to it by a screw, 42, the special function of which is to detach any type that may cling to the upper member of the mold. The register-piece 40 is held in place by screws 43 44, tapped into the body-block 13, and a screw, 45, entered into it after passing through the bed-plate A. The register-piece 50 is secured to the body-block 19 by screws 51 52, and to the bed-plate D by a screw, 53. These register-pieces form guides holding the two members of the mold in proper position laterally, the opposing guides consisting of cheek-pieces 60 70, secured, respectively, to the body-blocks 13 19 by screws 61 71.

The jet-pieces 80 90, which are stepped blocks that form an opening more or less great, as the upper and lower members of the mold are relatively adjusted, constitute the in-gate of the mold, within which the jet or surplus metal is cast upon the foot of the type. These jet-pieces were formerly simply secured to the bed-plates; but in order to hold them snugly in place and maintain a tight joint between them and the body-blocks and bed-pieces, to cause the foot of the type to be cast accurately, in the improved construction they are secured both to the body-block and to the bed-plates A D. Thus secured, these jet-pieces are prevented, when the molds contract, after being greatly expanded by the heat, from becoming separated from the body-block or bed-piece and forming a space into which the metal may run, and thus cause the foot of the type to be rough and ragged.

In the improved construction the jet-pieces are respectively held by four screws each, the piece 80 having two screws, 81 82, that hold it to the bed-plate A, and two screws, 83 84, that hold it to the bed-piece 10 and body-block 13. The piece 90 is similarly held by screws 91 92 passing through the bed-plate, and screws 93 94 entering the bed-piece 16 and body-block 19.

In this improved construction the cross-screws 83 84 and 91 92, which hold the jet-pieces to the body-blocks and bed-pieces, will, when the mold expands, expand with it, and consequently when it contracts will contract with it, and thus the jet-pieces will be constantly kept in proper place, or in close contact with the body-blocks and bed-pieces, and

hence no space will be opened between them and the body-blocks or bed-pieces to receive the molten metal and form a sprue that will 60 destroy the foot of the type. The solid construction of the body-blocks 13 19, removing the necessity of using screws to hold "lifts," provides room in the parts at the proper points to enable the use of the screws to hold 65 the jet-blocks in both directions.

These improvements permit the construction of type-molds at small expense, and produce a structure that may be continuously used for a long period of time without derangements of parts, necessitating stoppage and repair.

What is claimed is—

1. A type-mold the two members of which are each composed of a body-block and bed-piece abutting together and secured to the bed-plate, said body-blocks each being formed in a single piece and of a thickness suitably greater than the companion bed-pieces, to provide for the formation of the type-body, substantially as described.

2. A type-mold the two members of which are each composed of a solid body-block and bed-piece secured, respectively, to the bed-plate by screws and united together by a longitudinal screw, substantially as described.

3. In a type-mold, the combination, with the bed-piece, of nick-formers secured thereto by means of their lateral projections and recessed or undercut slots in the bed-piece, substantially as described.

4. In a type-mold, the combination, with the bed-piece, slotted, as described, to receive nick-formers, of the nick-formers and the abutting body-block, substantially as described.

5. In a type-mold consisting of two members, each composed of a solid body-block and bed-piece united to the bed-plate by screws, and jet-pieces united to the bed-piece by screws and to the body-block and bed-piece by screws, substantially as described.

6. In a type-mold, the combination, with the bed-piece, slotted, as described, to receive nick-formers, of the nick-formers provided with shoulders, as 3, and the abutting body-block, substantially as described.

In testimony whereof I have hereunto set my hand in the presence of two subscribing witnesses.

GEO. R. BACON.
